UNITED STATES PATENT OFFICE.

FRANKLIN P. VAN HOOK, OF CALDWELL, IDAHO.

POST-MOLD.

1,017,026.

Specification of Letters Patent.

Patented Feb. 13, 1912.

Application filed March 29, 1911. Serial No. 617,646.

To all whom it may concern:

Be it known that I, FRANKLIN P. VAN Hook, a citizen of the United States, residing at Caldwell, in the county of Canyon 5 and State of Idaho, have invented certain new and useful Improvements in Post-Molds, of which the following is a specification.

This invention relates to molds or forms 10 for making posts of concrete or other plastic materials.

One object of the invention is to provide a construction whereby a plurality of molds may be conveniently coupled together for 15 conjoint use and as readily and conveniently uncoupled when required.

One object of the invention is to provide simple and effective means for holding a series of retaining loops in, through or upon 20 a mold so as to be partially embedded in concrete or other plastic material forming the post, and so that the loops may be disconnected from the molds for the removal of the post.

25 The invention consists of the features of construction, combination and arrangement of parts hereinafter more fully described and claimed, reference being had to the accompanying drawings in which—

30 Figure 1 is a perspective view of a series of molds, constructed and assembled in accordance with my invention. Fig. 2 is a top plan view of one of the molds. Fig. 3 is a vertical longitudinal section thereof. Fig.

35 4 is a vertical transverse section through the assembled series of molds. Fig. 5 is a fragmentary transverse section in perspective of one of the molds, a post which has been formed therein, and one of the locking keys

40 showing the key detached and the post partially removed from the mold. Fig. 6 is a fragmentary detail outer side elevation of one of the walls of a mold showing a loop held in position by a locking key. Fig. 7 is

45 a section on line 7—7 of Fig. 6. Fig. 8 is a section on line 8—8 of Fig. 6.

Referring to the drawings "1" designates my improved mold, which is preferably made of sheet metal and of V-form in cross 50 section, said mold being open at each end and top and adapted for the formation of a post "2" of triangular form in cross section having a groove "10" the entire length of one of the triangular faces of said post.

55 The upper or free edges of the side walls

"3" and "4" of the mold are bent outward laterally to provide horizontal flanges "5" and "6," one of said flanges being bent inwardly to form a locking hook "7" and the other bent inwardly to form a locking hook 60 "8." The hook "7" overlies the flange "5" while the hook "8" underlies the flange "6," and are so formed as to be readily connected and disconnected as required.

The mold preferably tapers longitudinally for the production of a post of greater transverse dimensions at its base and tapering uniformly to its top, but this form of the mold and post is not essential. One of the side walls as the wall "3" is provided 65 with a longitudinal concavo-convex rib "9" having its convex side facing inwardly, said rib serving to provide a longitudinal retaining groove "10" in the face of the post. A series of transverse slots "11" is formed 70 in said wall "3" and directly across the rib when the latter is used.

Retainers made of wire or other metallic substance shown at "12" are provided to be 80 fixed in the face of the post at intervals determined by the relative arrangement of the slots "11." Each retainer comprises a single length of wire or other metallic substance having curved terminal anchoring arms "13" and a central loop or offset "14." 85 The arms "13" of the retainers are adapted to be embedded in the post on opposite sides of the groove "10" and the loops "14" of the retainers to project out and beyond the lowest surface of the groove in such a manner as to be adapted to hold a line wire, 90 supporting rod or strip seated in said groove or to them may be attached fencing or other desired material.

The mold may be supported in practice 95 in a suitable frame having portions on which the flanges "5" and "6" and other portions of the form bear, and portions to close and open ends of said molds.

In forming a post the retainers are first 100 placed in position with their arms disposed in the mold and their loops projecting exteriorly through the slots "11" in which position they are held by locking keys "15." The concrete or other plastic material is 105 then filled into the mold and tamped to the desired density level with the top of the mold after which the material is allowed to harden. Upon the sufficient hardening of the material, the keys are detached and the 110

formed posts removed, the retainers being embedded therein in the manner shown in Fig. "5."

Each key is formed of a single piece of 5 spring wire or other metal bent or formed in such a way as to provide terminal bearing arms "16" and "17" to seat against the rib, a finger piece "18" at the outer end of the arm "16" and a back turned spring 10 arm "19" extending from the free end of the arm "17." Between the arms "16" and "17" the wire or other metallic substance is bent or formed so as to provide a loop "20" having an inwardly projecting retainer 15 loop "14" so that the arms "16" and "17" rest against the rib and the spring arm "19" bears against the rib and one side of said loop, and until the offset "21" of the loop "20" snaps into locking engagement with 20 the bight of the loop "14," when the retainer and key will be held in position by the spring or wedge pressure of said key. The key may be withdrawn, by a reverse movement thus releasing the retainer.

25 The hooked flanges adapt two or more molds to be arranged in paralleled relation and interlocked for mutual supporting action and convenience in forming a series of posts at one time as shown in Figs. "1" and 30 "4." In so assembling the molds the hooked flange "5" of one mold is interlocked with the hooked flange "6" of an adjacent mold. When the molds are longitudinally tapered as shown they are assembled so that they 35 will alternately taper in opposite directions in the series as illustrated in Fig. "1" by which their flanges are brought into parallel relation for proper locking engagement.

From the foregoing description, the construction and mode of use of molds 40 constructed in accordance with my invention will be readily understood, and it will be seen that a simple and inexpensive type of mold and construction of means for holding 45 the retainers in position are provided, while the conveniences afforded in enabling a plurality of molds to be coupled for conjoint use will be readily appreciated.

Having thus described my invention, what

I claim and desire to secure by Letters Patent is,

1. A mold having a wall formed with a slot in combination with a metal retainer, having arms extending beyond one side of said wall and a looped portion to project 55 through the slot beyond the opposite side of said wall, and a key adapted to pass through said loop and having fixed arms and a spring arm to bear upon the latter named wall and having an offset to engage said 60 loop.

2. A mold having a wall formed with a slot in combination with a retainer, provided with a looped portion to extend through said slot, and a key adapted to be 65 slidably engaged with said looped portion, and having an offset to interlock therewith.

3. A mold having at one side an inset longitudinal concavo-convex rib provided with a cross slot, a metal loop having a central portion to project outwardly through the slot into the concavity of the rib and arms to extend laterally beyond the convex side of the rib, and a key to engage the central portion of the loop and concaved face 75 of the rib.

4. A mold having a concavo-convex rib provided with a cross slot therein, in combination with a metal loop to project through said slot with arms to project beyond the 80 inner face of the rib, and a sliding spring key to interlock with the loop and concaved face of the rib.

5. A mold having at one side a concavo-convex rib with one or more cross slots, a 85 metal loop adapted to be passed through said slot and having arms to project beyond the inner wall of the rib, and a key adapted to be slidably engaged with the loop and concaved face of the rib, and having an offset 90 to interlock with the loop.

In testimony whereof I affix my signature in presence of two witnesses.

FRANKLIN P. VAN HOOK.
